PARACHUTE

Filed May 5, 1930

Inventor

F. Howard Packard

By Clarence O'Brien
Attorney

UNITED STATES PATENT OFFICE

FRANCIS HOWARD PACKARD, OF BOARDMAN, OREGON

PARACHUTE

Application filed May 5, 1930. Serial No. 449,948.

This invention relates to new and useful improvements in parachutes and has for its primary object to provide, in a manner as hereinafter set forth, a device of this character embodying inflatable means adapted to render the same buoyant for the purpose of supporting a person who has descended into a body of water.

Other objects of the invention are to provide a parachute of the character described which will be simple in construction, strong, durable, efficient in its use and which may be manufactured at low cost.

All of the foregoing and still further objects and advantages of the invention may become apparent from a study of the following specification, taken in connection with the accompanying drawing, in which:—

The figure is a view in bottom perspective showing the parachute constructed in accordance with this invention in operative position.

Referring to the drawing in detail, it will be seen that the reference numeral 1 designates generally the body of a parachute comprising, as usual, the sections or lobes 2. The cords 3 are secured in the usual manner to the periphery of the body portion 1 and extend downwardly to a parachute harness 4 of any suitable construction.

All of the foregoing is conventional in parachute construction and form no part of this invention.

The invention comprises a plurality of pairs of inflatable bags 5 which are secured on the outer portions of certain of the sections or lobes 2 of the body 1 of the parachute. The bags of each pair are spaced from each other the width of one section or lobe and said pairs of bags are disposed in circumferentially spaced relation around the body portion 1 of the parachute. The preferred method of constructing the bags 5 is by securing the marginal portion of a flat sheet of flexible material to the sections or lobes 2 and in this manner said sections or lobes constitute one side of the bags and the sheets constitute the other side of said bags. It is understood, of course, that the connection or joint between the sheets and the sections or

lobes 2 is air and water tight to prevent leakage of water thereinto or the escape of air therefrom. This may be accomplished in any approved manner. Communicating with each of the bags 5 is an inflating valve 6 and said valves may be of any desired type. Preferably, the valve 6 projects from the peripheral ends of the bags in the manner clearly illustrated in the drawing.

In use, should the person using the parachute descend in a body of water, he has only to place one of the valves in his mouth and inflate the respective bags 5. He may then inflate the adjacent bags of that particular pair after which he may support himself on the intermediate section or lobe in which position the bags 5 which have been inflated will be disposed on opposite side of the body and function as water wings.

It is believed that the many advantages of a parachute constructed in accordance with this invention will be readily understood, and although the preferred embodiment of the invention is as illustrated and described, it is to be understood that changes in the details of construction may be had which will fall within the scope of the invention as claimed.

What is claimed is:—

A parachute of the character described comprising a series of radiating connected lobes, flexible substantially rectangular sheets mounted on certain of the lobes and having their marginal portions connected thereto in a manner to provide a leak-proof joint therebetween, said sheets, in conjunction with the lobes, constituting bags for the reception of air, the side edges of the sheets being disposed flush with the longitudinal edges of the lobes upon which the sheets are mounted, said sheets being arranged in spaced pairs, one of the lobes being disposed between the bags constituting each pair, and an inflating valve operatively connected with each of the bags.

In testimony whereof I affix my signature.
FRANCIS HOWARD PACKARD.
